RUCHING DEVICE

Charles Seaman, Jamaica Estates, Long
Island, N. Y.

Application April 10, 1936, Serial No. 73,636

20 Claims. (Cl. 112—134)

This invention relates to a sewing machine or an attachment for making pleats or ruching.

An object of the invention is to provide a device for making pleats of a uniform predetermined size which may be readily controlled by suitable adjustment of the device.

Another object is to provide a simple, convenient, efficient and dependable device of the above type.

These objects and others which will be apparent as the nature of the invention is more fully disclosed, are accomplished by feeding a tape, with or without a base material, under a presser foot which is periodically elevated to release the material and to interrupt the feed thereof and, at the same time, continuously feeding a ruching material under an auxiliary presser foot. The tape is fed through a spring guide which acts to pull back or return the tape and the base material a predetermined amount when the feed is interrupted by elevation of the presser foot. Since the feed of the ruching material is not interrupted, the latter is caused to loop or gather into a pleat, the size of which is determined by the amount of return of the tape and the rate of feed of the ruching material. The amount of return which is effected by the spring guide is determined by the position of an adjustable stop. The size of the pleat can accordingly be controlled by adjusting the position of the stop and the time during which the feed of the tape is interrupted by elevation of the presser foot.

Although the novel features which are believed to be characteristic of this invention will be more particularly pointed out in the claims appended hereto, the broader aspects of the invention will be better understood by referring to the following description taken in connection with the accompanying drawings, forming a part thereof, in which certain preferred embodiments of the invention are set forth for purposes of illustration.

In the drawings,

Figure 1 is a top plan view of the ruching device as applied to the base of a sewing machine head, with parts broken away to more clearly illustrate the details of construction;

Figure 2 is a section taken on the line 2—2 of Figure 1;

Figure 3 is a broken perspective of the ruching device;

Figure 4 is a plan view of a ruching which is made by the device illustrated in Figures 1 to 3;

Figure 5 is a section of the ruching taken on the line 5—5 of Figure 4;

Figure 6 is a section similar to Figure 2, but

showing a different embodiment of the invention;

Figure 7 is a detail view of the presser foot and guide shown in Figure 6;

Figure 8 is a plan view of a ruching made by the device shown in Figures 6 and 7; and

Figure 9 is a section of the ruching taken on the line 9—9 of Figure 8.

In the following description and in the claims, certain specific terms are used for convenience in referring to various details of the invention. It is to be understood, however, that these terms are to be given as broad an interpretation as the state of the art will permit.

Referring to the drawings more in detail, the invention is shown as applied to a sewing machine head 10 having a needle bar 11 (Figure 2) carrying a needle 12 which is actuated by suitable driving means (not shown). The head 10 is also provided with a presser foot bar 13 carrying a main presser foot 14 which holds the material in driving engagement with a feed dog 15 extending through an aperture 16 in the base 17 of the sewing machine head, and is operated in the usual manner to feed the material to the needle for stitching.

The presser foot bar 13 is provided with an arm 18 engaging a cam lever 19 having a handle 20 which is adapted to raise the presser foot 14 out of engagement with the material to permit the material to be adjusted in the machine. A spring 21 serves to hold the presser foot 14 in feeding position. The presser foot 14 is periodically elevated by means of a lever 22 pivoted, as at 23, to the head of the machine and carrying a pin 24 which extends through an elongated slot 25 in a link 26 attached to the arm 18. The lever 22 is driven by suitable mechanism (not shown) to periodically elevate the presser foot 14 so as to release the pressure on the material and to interrupt or retard the feed thereof. The lever 22 may be operated in any suitable manner. One type of mechanism which may be used for actuating the same is disclosed in my Patent No. 2,025,530, dated December 24, 1935, for Shirring device.

The ruching device comprises a plate 30 which is attached to the base 17 of the sewing machine by suitable means, such as screws 31 (Figures 1 to 3). The plate carries a block 32 to which a pair of bars 33 and 34 are secured by screws 35. A cross bar 36 joins the bars 33 and 34 near their free ends for providing a supporting frame for the guide mechanism to be described.

A resilient lever 39 is secured to the bar 33,

as by a screw 40. One end of this lever is bent downwardly to form an auxiliary presser foot 41 which is positioned in advance of the main presser foot 14 and cooperates with a portion of the feed dog 15 for holding the material in driving engagement therewith. The other end of the lever 39 extends over the bar 34 to provide a handle 42 to facilitate adjustment thereof. A release lever 43 is pivoted to the bar 33 by a screw 44 and is adapted, when rotated in the direction of the arrow in Figure 1, to press against the under surface of the lever 39 for raising the auxiliary presser foot 41 from the material.

15 A guide member 45 is secured to a bar 46 which is slidably held in the block 32, as by an adjusting screw 47. The guide member 45 comprises a plate 48, one side of which is bent over to form a flange 49 under which the ruching material 50 is fed. A tension gate 51 may be secured to the block 32 for applying tension to the ruching material 50 so as to insure the proper feeding thereof. A guide wire 52 may be attached to the bar 34 to guide the ruching material from the tensioning gate 51 to the guide member 45. From the guide member 45 the ruching material 50 passes under the auxiliary presser foot 41 in driving engagement with the feed dog 15 by which it is fed to the needle for stitching in the usual manner.

30 The ruching device also includes a spring guide 55 having a loop 56 at the end thereof which is adapted to feed a tape 57 to the main presser foot 14. The spring guide 55 is secured by screws 58 to a cover plate 59. The cover plate 59 is secured to the bar 33 by means of screws 60 and is adapted to prevent the hands of the operator from accidentally coming in contact with the various parts and interfering with the feed. The cover plate 59 also serves as a guide for the fabric or base material. The proper tension is applied to the tape 57 by means of tension plates 64 and 65. The plate 64 may be rigidly secured to the bar 34. 35 The plate 65 may be adjustably secured by means of a spring 66, the tension of which is adjusted by means of an adjusting nut 67, the arrangement being such that the tape 57 passes between the plates 64 and 65 and is held under a tension which is determined by the pressure exerted on the plate 65 by means of the spring 66.

40 A tape guide 70 is adjustably mounted on the cover plate 59 by means of a screw 71 passing through an elongated slot 72 formed on the arm 73 attached to the tape guide. The edge 74 of the tape guide 70 which is nearest the path of the needle forms a stop to limit the amount of return of the tape in the manner to be pointed out. Suitable adjustment of the tape guide 70 may be made by means of the screw 71 and slot 72 for varying the position of the stop as required for making pleats of different sizes.

45 The tape 57 passes between the tension plates 64 and 65, through the spring guide 55, through the tape guide 70, over the auxiliary presser foot 41, and under the main presser foot 14 by which the feed thereof is controlled. The base material 75 to which the ruching is to be stitched passes over the cover plate 59 and under the main presser foot 14 in the usual manner.

50 In the operation of the ruching device, the ruching material 50 is fed under the auxiliary presser foot 41 in driving engagement with the feed dog 15 and is continuously fed to the nee-

5 dle for stitching. The tape 57 and the base material 75 are fed over the auxiliary presser foot 41 and under the main presser foot 14. When the main presser foot 14 is in its lower position, the tape 57 and the base material 75 are held in driving engagement with the feed dog 15 and are fed to the needle at a rate corresponding to the rate of feed of the ruching material. While the tape 57 is being fed in the above-mentioned manner, the tension thereof, 10 which is controlled by the tension plates 64 and 65, causes the spring guide 55 to bend towards the needle into the position indicated in dotted lines in Figure 1. The amount of deflection of the spring guide 55 depends upon the tension of the tape 57 and the amount of feed.

15 During the feeding operation above described, the presser foot 14 is in feeding position. The presser foot 14, however, is periodically elevated, as, for example, by the mechanism described in the above-mentioned patent. When the presser foot 14 is elevated, the pressure on the base material 75 and on the tape 57 is released, and the feed of the base material and tape is interrupted. When this occurs, the 20 spring guide 55 returns to its original position, as shown in full lines in Figure 1, pulling back or returning the base material and the tape until the last stitch engages the edge 74 of the tape guide 70 and is stopped thereby. During this time the ruching material 50 continues to be fed by reason of the pressure exerted thereon by the auxiliary presser foot 41. This feeding of the ruching material and the pulling back of the tape and base material cause the 25 ruching material to loop and form a pleat, the size of which is determined by the position of the edge 74 of the tape guide 70 and by the amount of feed of ruching material while the presser foot 14 is thus elevated. When the 30 presser foot is again brought into feeding position, the tape 57 and the base material 75 are fed along with the ruching and the pleat is 35 permanently stitched to the base material.

40 A ruching formed in this manner is shown, for example, in Figure 4. It will be noted that the tape 57 is positioned between the base material 75 and the ruching material 50. This tape serves as a strengthening means for the product. In some instances the base material 75 may be omitted, in which case the ruching is attached only to the tape 57. In this way the ruching may be made and sold to the trade separately.

45 It is apparent that in the above device the tension on the tape 57 must be sufficient to actuate 50 the spring guide 55.

55 The size of the pleats may be controlled by adjusting the position of the tape guide 70 in the manner above mentioned and by varying the timing of the actuating mechanism for the presser 60 foot 14. It is obvious that the tape guide 70 may constitute a folder or that the tape may be pre-folded before it is applied thereto if it is desired to apply the tape in more than one thickness. Furthermore, the ruching material may be positioned in any desired relationship to the base material. It may, for example, be applied at the edge of the base material. The edge of said material may also be folded to form a hem by the provision of a folder, as more fully set forth in 70 the patent above mentioned.

75 In the embodiment of the invention illustrated in Figures 6 and 7, the various elements, with the exception of the guide means for the tape 57, are similar to those enumerated above and have 75

been given the same reference characters. The tape 57 in this embodiment is fed to the presser foot 14 above the base material 75. The tape is fed through the tensioning gate 80 comprising a pair of tension plates 81 held by a spring 82, the pressure of which is adjusted by an adjusting nut 83. The tension gate 80 is mounted upon a spring lever 84 which may be held by a screw 85 mounted on the top of the sewing machine head 10. A tape guide 86 is provided which is located adjacent the front of the presser foot 14 and may be secured thereto. The tape guide 86 may also carry a guide loop 87. The end 88 of the tape guide 86 forms a stop which limits the return of the tape when the pressure of the presser foot 14 is released.

In the operation of this embodiment, the spring lever 84 is deflected due to the pull of the tape 57 as the same is fed to the needle for stitching. When the pressure on the tape 57 is released by reason of elevation of the presser foot 14, the spring lever 84 returns to its original position, thereby pulling back or returning the tape 57 and forming the pleat. The operation is otherwise identical with that described above. It will be noted that in this embodiment the tape 57 is secured beneath the base material 75 and is concealed thereby, as illustrated in Figures 8 and 9. The device can also be used to make separate ruching by omitting the base material and stitching the ruching material directly to the tape 57.

It is to be understood that suitable means may be provided for adjusting the position of the tape guide 86 with respect to the presser foot 14 so as to vary the size of the pleat. In some instances the guide 86 may be independently supported by a suitable bracket (not shown) which may be attached to the cover plate 59 in the same manner as the guide 70 of Figure 1.

Although certain preferred embodiments of the invention have been described in detail for purposes of illustration, the invention is not to be limited thereto. Various changes and modifications may be made therein as will appear to a person skilled in the art. Hence, the invention is to be limited only in accordance with the following claims when interpreted in view of the prior art.

I claim:

1. In a sewing machine, a feed dog, a presser foot to hold a first material in feeding engagement therewith, means to continuously feed a second material through said machine for stitching to said first material, means to periodically release the pressure of said presser foot on said first material for interrupting the feed thereof, and means to return the first material a predetermined amount when the feed is thus interrupted for thereby forming a fold or pleat in the second material.

2. In a sewing machine, a reciprocating needle, means to feed a first and a second material to the path of the needle for stitching, means for periodically interrupting the feed of said first material, and means to return the first material a predetermined amount when the feed is thus interrupted for thereby forming a fold or pleat in the second material.

3. In a sewing machine, a feed dog, a main presser foot to hold a first material in feeding engagement therewith, an auxiliary presser foot cooperating with a portion of the feed dog independently of the main presser foot to hold a second material in feeding engagement therewith, means to periodically release the pressure of the

main presser foot on said first material for interrupting the feed thereof, and means to return the first material a predetermined amount when the feed is thus interrupted for thereby forming a fold or pleat in the second material.

4. In a sewing machine, a reciprocating needle, means to feed a first material to the path of the needle for stitching, independent means to feed a second material to the path of the needle for stitching, means to periodically release the first feed means, and means to return the first material a predetermined amount when the feed thereof is thus released for thereby forming a fold or pleat in the second material.

5. In a sewing machine, a reciprocating needle, means for continuously feeding a ruching material to the path of the needle for stitching, means for feeding a second material to the path of the needle for stitching, means to periodically interrupt the feed of said second material, and spring means to return the second material a predetermined amount when the feed is thus interrupted for thereby causing the ruching material to form in a fold or pleat.

6. In a sewing machine, a feed dog, a main presser foot to hold a first material in feeding engagement therewith, an auxiliary presser foot cooperating with a portion of the feed dog independently of the main presser foot to hold a second material in feeding engagement therewith, a spring guide means for said first material, means whereby the feeding of said first material through said guide means causes deflection thereof, and means to periodically release the pressure of the main presser foot on said first material to interrupt the feed and to permit the spring guide means to return to its original position thereby pulling back or returning the first material and forming a fold or pleat in the second material.

7. In a sewing machine, a reciprocating needle, means for continuously feeding a ruching material to the path of the needle for stitching, means for feeding a second material to the path of the needle for stitching, means to periodically interrupt the feed of said second material, means to pull back or return the second material when the feed is thus interrupted, and an adjustable stop to limit the amount of said return whereby the ruching material is caused to form in a fold or pleat of a predetermined size.

8. In a sewing machine, a reciprocating needle, means for continuously feeding a ruching material to the path of the needle for stitching, means for feeding a second material to the path of the needle for stitching, means to periodically interrupt the feed of said second material, means to pull back or return said second material when the feed is thus interrupted, and a guide means through which the second material passes on its way to the needle, said guide means constituting a stop to limit the return of the second material so as to form a fold or pleat of a predetermined size in the ruching material.

9. In a sewing machine, a reciprocating needle, means for continuously feeding a ruching material to the path of the needle for stitching, means for feeding a second material to the path of the needle for stitching, means to periodically interrupt the feed of said second material, means to pull back or return the second material when the feed is thus interrupted, and a guide means through which the second material passes on its way to the needle, said guide means being positioned to engage the last stitch and limit the

return of the second material so as to form a fold or pleat of a predetermined size in the ruching material.

10. In a sewing machine, a reciprocating needle, means for continuously feeding a ruching material to the path of the needle for stitching, means for feeding a second material to the path of the needle for stitching, means to periodically interrupt the feed of said second material, 5 means to hold said second material under a predetermined tension, and a spring member actuated by said second material in response to the feeding movement thereof, said spring member being arranged to pull back or return said second material a predetermined amount when the feed thereof is interrupted.

11. In a sewing machine, a reciprocating needle, means to feed a ruching material to the path of the needle for stitching, independent 20 means to feed a base material and a tape to the path of the needle for stitching the same to the ruching material, means to periodically release the last feed means, and means cooperating with the tape to return the tape and base material a 25 predetermined amount when the feed thereof is thus released for thereby forming a fold or pleat in the ruching material.

12. An attachment for a sewing machine having a reciprocating needle and means to feed a first 30 and a second material to the path of the needle for stitching, said attachment having means for periodically interrupting the feed of said first material, and means to return the first material a predetermined amount when the feed is thus interrupted for thereby forming a fold or pleat in the second material.

13. An attachment for a sewing machine having a feed dog and a main presser foot to hold a first material in feeding engagement therewith, 40 said attachment comprising an auxiliary presser foot cooperating with a portion of the feed dog independently of the main presser foot to hold a second material in feeding engagement therewith, means to periodically release the pressure 45 of the main presser foot on said first material for interrupting the feed thereof, and means to return the first material a predetermined amount when the feed is thus interrupted for thereby forming a fold or pleat in the second material.

14. An attachment for a sewing machine having a reciprocating needle and means for continuously feeding a ruching material to the path of the needle for stitching, said attachment comprising means for feeding a second material to 55 the path of the needle for stitching, means to periodically interrupt the feed of said second material, and spring means to return the second material a predetermined amount when the feed is thus interrupted for thereby causing the ruching material to form in a fold or pleat.

15. An attachment for a sewing machine having a feed dog and a main presser foot to hold a first material in feeding engagement therewith, 65 said attachment comprising an auxiliary presser foot cooperating with a portion of the feed dog independently of the main presser foot to hold a second material in feeding engagement therewith, a spring guide means for said first material, means whereby the feeding of said first material through said guide means causes deflection thereof, and means to periodically release the pressure 70 of the main presser foot on said first material to

interrupt the feed and to permit the spring guide means to return to its original position thereby pulling back or returning the first material and forming a fold or pleat in the second material.

16. An attachment for a sewing machine having a reciprocating needle and means for continuously feeding a ruching material to the path of the needle for stitching, said attachment comprising means for feeding a second material to the path of the needle for stitching, means to 10 periodically interrupt the feed of said second material, means to pull back or return the second material when the feed is thus interrupted, and an adjustable stop to limit the amount of said return whereby the ruching material is caused to form in a fold or pleat of a predetermined size. 15

17. An attachment for a sewing machine having a reciprocating needle and means for continuously feeding a ruching material to the path 20 of the needle for stitching, said attachment comprising means for feeding a second material to the path of the needle for stitching, means to periodically interrupt the feed of said second material, means to pull back or return said 25 second material when the feed is thus interrupted, and a guide means through which the second material passes on its way to the needle, said guide means constituting a stop to limit the return of the second material so as to form a 30 fold or pleat of a predetermined size in the ruching material.

18. An attachment for a sewing machine having a reciprocating needle and means for continuously feeding a ruching material to the path 35 of the needle for stitching, said attachment comprising means for feeding a second material to the path of the needle for stitching, means to periodically interrupt the feed of said second material, means to pull back or return the 40 second material when the feed is thus interrupted, and a guide means through which the second material passes on its way to the needle, said guide means being positioned to engage the last stitch and limit the return of the second 45 material so as to form a fold or pleat of a predetermined size in the ruching material.

19. An attachment for a sewing machine having a reciprocating needle and means for continuously feeding a ruching material to the path 50 of the needle for stitching, said attachment comprising means for feeding a second material to the path of the needle for stitching, means to periodically interrupt the feed of said second material, means to hold said second material 55 under a predetermined tension, and a spring member actuated by said second material in response to the feeding movement thereof, said spring member being arranged to pull back or return said second material a predetermined 60 amount when the feed thereof is interrupted.

20. The method of making a ruching which comprises continuously feeding a ruching material to a needle for stitching, feeding a second material to the needle for stitching to the first 65 material, periodically interrupting the feed of the second material, and pulling back the second material a predetermined amount when the feed is thus interrupted so as to form a fold or pleat of predetermined size in the first material. 70

CHARLES SEAMAN.
